COMBINED WHEEL AND TIRE

Millard Fillmore Harty, Jr., Bloomfield Hills, Mich.,
assignor to Motor Wheel Corporation, Lansing, Mich.

Continuation-in-part of abandoned design application Ser.
No. 140,014, May 3, 1971. This application July 20,
1973, Ser. No. 381,177

Term of patent 14 years

Int. Cl. D12—15; D12—16
U.S. CL. D12—135

Fig-1

Fig -3

Fig -2

FIG. 4FIG. 5FIG. 6FIG. 7

FIG. 1 is a front perspective view of a combined wheel and tire showing my new design;

FIG. 2 is a front elevational view thereof;

FIG. 3 is a sectional view thereof taken along line 3-3 in FIG. 2;

FIG. 4 is a front elevational view thereof, without the wood grain surface ornamentation on the radiating flanges and outboard side of the wheel rim;

FIG. 5 is a front perspective view of a combined wheel and tire showing a second embodiment of my new design;

FIG. 6 is a front elevational view of the embodiment shown in FIG. 5; and

FIG. 7 is a sectional view of the embodiment shown in FIG. 5 taken along the line 7-7 in FIG. 6.

The characteristic feature of my design resides in the outboard side of the tire and the outboard face of the wheel being specially molded to match up with one another and provide a smooth transition from the wheel to the tire.

The wood graining shown in FIGS. 1 and 2 is surface ornamentation on the elastomeric material applied to the wheel.

This is a continuation-in-part of design application Ser. No. 140,014, filed May 3, 1971, and now abandoned.

I claim:

The ornamental design for a combined wheel and tire, substantially as shown and described.
